United States Patent Office.

NORMAN MAYBEE AND ABRAM MAYBEE, OF MONROE, MICHIGAN.

Letters Patent No. 78,220, dated May 26, 1868.

IMPROVED SCRAPER.

The Schedule referred to in these Letters Patent and making part of the same.

TO WHOM IT MAY CONCERN:

Be it known that we, NORMAN MAYBEE and ABRAM MAYBEE, of Monroe, in the county of Monroe, and State of Michigan, have invented a new and useful Improvement in Scrapers; and we do declare that the following is a true and accurate description thereof, reference being had to the accompanying drawings, and to the letters of reference marked thereon, and being a part of this specification.

The nature of this invention consists in so constructing a scraper that it can be used in all kinds of soils, particularly those wherein are found small roots, rank grasses, &c., that may be provided with cutting-knives in the body of the scraper, and with cutting-blades arranged upon the draught-bail, operating against cutting-edges upon the sides of the scraper, so that roots, grasses, &c., will not clog it.

In order to accomplish this end, we build a scraper, A, provided with proper handles, B, and a draught-bail, C. Upon this bail C are placed the share-blades D, which operate against proper cutting-edges, E, upon the sides of the scraper, at or near the point at which the draught-bail is pivoted.

The bottom of the scraper is corrugated upon its front or cutting-edge. These corrugations are provided at their base or inner extremity with cutting-blades F. The points, G, between these corrugations are also provided with cutting-blades, H. These cutting-blades are all designed to cut off any roots or other like obstructions, which otherwise would clog up and impede the operation of the scraper.

It will be observed that the draught-bail is bent at its rear extremities, so as to describe nearly or quite a quarter of a circle from the point to which it is pivoted, upward and forward, which enables us to keep the front of the scraper in the ground with much less labor to the operator.

What we claim as our invention, and desire to secure by Letters Patent, is—

The combination of the scraper A, draught-bail C, and handle B, all constructed and arranged substantially as described, and for the purposes specified.

NORMAN MAYBEE,
ABRAM MAYBEE.
